UNITED STATES PATENT OFFICE.

THOMAS G. TURNER, OF NEW YORK, N. Y.

FIRE-EXTINGUISHER.

SPECIFICATION forming part of Letters Patent No. 392,936, dated November 13, 1888.

Application filed August 29, 1888. Serial No. 284,097. (No model.)

To all whom it may concern:

Be it known that I, THOMAS G. TURNER, a citizen of the United States, and a resident of New York, in the county of New York and State of New York, have invented certain new and useful Improvements in Fire-Extinguishers, of which the following is a specification.

My invention relates to that class of fire-extinguishers in which a pressure of gas (generated at the time of use) projects a chemical fluid onto the fire without the gas mingling with the fluid and acting simply as a piston to expel the fluid.

In Patent No. 381,658 of the United States, issued to me April 24, 1888, I describe one form of construction designed for this purpose; and the invention for which I now make application for patent is intended to more fully attain the object sought, which is the separation of the elastic gas, acting as a piston, from the chemical fluid used as the extinguishing agent. I accomplish this by the use of an elastic or flexible bag inside the body of the extinguisher surrounding the parts or portions of the machine holding the chemicals, which, when mingled, generate the gas-pressure, the mingling being the result of inverting the entire apparatus.

In the accompanying drawings I show two forms of the bag surrounding the vessels holding the alkali and acid ready for use.

In each of the drawings like letters denote similar parts.

A is the main body of the extinguisher.

35 B is a screw for holding the cover to the opening in A in position.

C is a brace or strap to sustain the reaction of B.

D is the cap or cover to main vessel, and in Figure 2 it is shown as extending down into the body of the extinguisher and acting as a stay for the upper end of inner vessel, N, containing the gas generating ingredients and surrounded by bag T.

45 F F are two caps for closing the ends of tube N, which may be blown off by the expanding gases.

K is a gasket for closing the opening of vessel A under cap D.

50 N is an inner tube for containing the gas-generating ingredients in vessels O and P, one

above the other, as shown; or two inner tubes could be used to hold the acid and alkali, of the same size and length, and the tube N need not be used.

In this application I do not wish to confine myself to any special form of inner tubes for containing the acid and alkali; but what I do wish to cover is the confining of the acid and alkali and the gas resulting from their mingling in suitable vessels inside of an elastic bag or cover, in which the gas will accumulate and be held and prevented from coming into contact with the extinguishing-fluid contained in the main body of the extinguisher, 65 at the same time the gas acting as an elastic piston to force out the fluid when the vent W is opened.

In the drawings, Fig. 1, the elastic bag T is shown as attached at its mouth to gasket K. 70 In Fig. 2 the bag is shown as tied at its mouth by a piece of string or tape. In each case the vessels containing the acid and alkali are entirely inclosed in the bag and their contents prevented from mingling with the contents of 75 the main vessel. When the vessel is inverted, the acid and alkali are mingled and gas is liberated, the bag acting as a diaphragm between the gas and the extinguishing-fluid. Upon opening the vent W the extinguishing-fluid is 80 forced out, and the bag gradually expands under the pressure of the gas till all of the fluid will be expelled, when the bag will burst upon coming in contact with the sharp corners of the vent W (but not before) and the pressure 85 be blown off. The bag of course being destroyed, a new one is required for each charging of the machine; but, being made at small expense, this is not an objection to this style of machine.

In all machines in which the acid and alkali are contained in a sealed elastic bag, as shown, the vessels must be open, so that the contents of the two will mingle when the extinguisher is inverted. I have found that the 90 floating of some lighter liquid on the surface of the acid will act as a seal to prevent the fumes from rising and setting up a false action or a premature generation of gas. I greatly prefer this plan of sealing to the use of any 95 form of non-corrosive valve—such as glass, rubber, or lead balls—as shown in Fig. 1,

marked S. The heavy black lines at M in vessel P denote the position of this lighter fluid.

Having thus described my invention, what I claim as new is—

1. In a chemical fire-extinguisher, the combination of an outer vessel containing fire-extinguishing fluid, an elastic or expanding gas-tight bag situated within said outer vessel, and 10 quantities of acid and alkali normally separated one from the other within said bag and adapted to be mixed when used, all substantially as described.
2. In a chemical fire-extinguisher, the combination of an outer vessel partially filled with fire-extinguishing fluid, an elastic or expanding gas-tight bag placed within said outer vessel and normally only partially surrounded by the extinguishing fluid, and quantities of acid 20 and alkali normally separated one from the other within said bag and adapted to be mixed when used, all substantially as described.
3. In a chemical fire-extinguisher, the com-

bination of an outer vessel having a vent, W, containing fire-extinguishing fluid, an elastic 25 or expanding gas-tight bag placed within said outer vessel, and two inner receptacles, O P, within the bag for separately containing one an acid and the other an alkali, all substantially as described.

4. In a chemical fire-extinguisher, the combination of an outer vessel containing fire-extinguishing fluid, an elastic or expanding gas-tight bag placed within said outer vessel, two 30 receptacles, O P, one containing an acid and the other an alkali, placed within said bag, and a film of oil floated upon the acid to prevent its fuming, all substantially as described.

Signed at New York, in the county of New York and State of New York, this 31st day of 40 July, A. D. 1888.

THOMAS G. TURNER.
